UNITED STATES PATENT OFFICE.

MICHAEL RUDOMETOFF, OF GATTSCHINA, RUSSIA.

PROCESS OF MULTICOLOR OR POLYCHROMATIC PRINTING.

SPECIFICATION forming part of Letters Patent No. 714,953, dated December 2, 1902.

Application filed June 6, 1902. Serial No. 110,561. (No specimens.)

To all whom it may concern:

Be it known that I, MICHAEL RUDOMETOFF, engineer, a subject of the Czar of Russia, residing at Gattschina, Government of Petersburg, Russia, have invented certain new and useful Improvements in the Process of Multicolor or Polychromatic Printing; and I do hereby declare the following to be a full, clear, and exact description of the invention, such as will enable others skilled in the art to which it appertains to make and use the same.

The present invention relates to multicolor or polychromatic printing in typographic-printing presses by means of a single form; and it consists of the particular steps or process hereinafter set forth, and particularly pointed out in the claims.

Prints of the above character have of late been made by first transferring the various colors from separate stereotypes or blocks upon which they have been produced by any suitable process to a single printing-form and then transferring the whole combination of colors to the paper by one printing operation.

Such a process is shown and described in the United States Patent to Orloff, No. 632,322, of September 5, 1899. This may be taken as illustrative of the general type of process upon which my invention is an improvement. The

transfer of the separate single-color prints to the collecting-form was therein effected by means of intermediate transfer-rollers, which carried the color from each inking block or form to the said collecting-form. In this class

of printing there is a danger that any one of the intermediate rollers may take off a little of the other wet colors from the collecting or printing form and transfer it back to the inking-form and thence to the single-color roller

and to the whole set of rollers and that consequently the subsequent prints from the combination or collecting form would gradually become more and more impure in color, owing to the continual mixing of the colors. This

disadvantage may be obviated to a great extent by depositing the color upon the printing-form in a series of parallel lines, which may be done by providing the transfer-rollers with flutings, in which case a lined or half-toned impression will be produced on the printing-form. If, however, several lined impressions are consecutively transferred to the form,

there is danger of producing a moire-pattern effect—i. e., an effect similar to that of "watered" fabrics. This effect may be avoided by placing the lines of each separate system at not too acute an angle to those of the other systems, and this may be done in such a press as above referred to by employing fluted transfer-rollers for the various colors, the flutings of each roller being set at an angle to those of the other rollers. A very slight mingling of the colors may take place on the printing-form at the points of intersection of the lines of color; but this would give rise to but a very slow soiling of the rollers during the printing. Even this disadvantage may be comparatively easily obviated by making the flutings upon the rollers for the various colors of different depths and by providing corresponding flutings on the collecting or printing form. If this is done, the transfer-rollers will not contact with the color already upon the collecting-form, even at the points of intersection of the lines of color. A most accurate register will be attained by providing the form with recesses which correspond in depth exactly with the flutings of the rollers. The engagement of the flutings with the recesses of the printing-form will then insure exact registration during the printing, even if the machine does not run quite evenly, since the said flutings will engage exactly with the grooves or recesses of the form. In this latter case it is advantageous not to provide the collecting or printing form with flutings over its whole surface, since these might form impressions in the open parts of the picture—for instance, on the margin. For this purpose all the pattern-blocks are registered on the collecting-form and etched in relief before the flutings are formed, so that these latter will not appear on the ground of the form or outside the margin of the picture.

The drawings accompanying herewith illustrate the manner and a means of carrying out my invention.

Figure 1 is a side elevation and partial section of a flat or bed press designed for carrying out my invention. Fig. 2 is a plan of the same except that the inking mechanism is omitted to avoid covering more essential features. Figs. 3 and 4 are respectively side elevation and plan of a cylinder-press adapt-

ed to carry out my invention. Fig. 5 is a section, on an exaggerated scale, designed to illustrate the character of surface employed for the printing-form in one manner of carrying out my invention; and Fig. 6 is a diagram illustrative of the manner of printing the various colors.

The drawings illustrate a flat or bed press and a cylinder-press adapted to make use of my process and resembling in its general features the press of the Orloff patent, before referred to. This has a collecting and printing form F, inking-forms F', F², and F³, to each of which ink of its particular color is applied, as by the rollers D and reservoir d, and from which the ink is transferred by its particular transfer-roller B', B², or B³, each of said rollers touching only one of the primary or inking forms F', F², and F³, but all engaging and transferring ink to the collecting and printing form F.

Upon each of the primary or inking forms F', F², and F³, I have shown by a series of parallel lines that portion of a picture which is to be printed in that particular color. These when combined upon the collecting-form F form a complete picture. The transfer-rollers B', B², and B³ are journaled in a frame A, which, with its transfer and inking rollers, may be moved along the bed, so as to transfer ink from each primary form to the collecting-form. The transfer-rollers have gears g, secured thereto and meshing with racks G, whereby the proper registry of the rollers upon the collecting-form may be secured. The journaling of the rollers in the frame A is by slots, as shown at b, so that a slight rise and fall of the rollers may be permitted sufficient to prevent contact of any transfer or inking roller with any other inking-form than its own. This is secured by means of wheels H on the roller-shafts engaging cam-strips h on the bed, all in a usual and well-known manner.

The transfer-rollers are shown as grooved or fluted, the flutings in roller B' being circumferential, those in roller B² being diagonal, and those in roller B³ being longitudinal thereof, although any other suitable arrangement might be used.

The forms are etched or otherwise prepared in any suitable manner, each with that particular part of the picture which is to be in one color. After inking the transfer-rollers take up ink and transfer it to the collecting or printing form. By reason of the fluting of the surfaces of the transfer-rollers the ink is deposited upon the collecting-form as series of lines, of which the different series may or may not overlap.

In Fig. 6 the process is well illustrated. This illustrates a circle having three colors represented by the series of lines 1, 2, and 3, each covering a zone extending across the circle and each of a width to include at each end an arc of sixty degrees, each zone being spaced

sixty degrees from each of the others. This forms at the center a hexagonal figure 123, which has all three colors thereon and is therefore a composite of these three colors. Outside of this hexagon are a series of equilateral triangles 12, 13, and 23, each of which is a composite of two colors represented by the individual numerals of which their reference character is composed, and between these triangles are the figures 1, 2, and 3, each of which has only one color thereon.

While the process above outlined may be carried out upon an unruled or smooth collecting-form, if the collecting or printing form be ruled or fluted to correspond with the flutings upon the transfer-rollers, so that the ribs or projections of the transfer-rollers enter the grooves of the form, thereby depositing their ink at the bottom of said grooves, and, further, if each set of grooves be of a different depth from the others, there will be no actual overlapping or superposition of the wet ink, and consequently no smearing or mixing of colors.

In Fig. 5 I have attempted to show diagrammatically and on an exaggerated scale how such a form would appear in section. In this 4 represents the shallowest grooves, corresponding, for instance, with the circumferential grooves or flutings of the transfer-roller B'; 5, the next depth, corresponding with the diagonal grooves or flutings of roller B², and 6 those which are at right angles with the first ones 4, corresponding with the longitudinal grooves or flutings of the transfer-roller B³. While this figure is upon a very much exaggerated scale, it serves as a diagram to make clear the manner of forming the grooves or flutings. These grooves or flutings would of course be of no such size as are therein shown. Exaggeration is, however, necessary to clearly illustrate the true facts.

Figs. 3 and 4 show a cylinder-press designed for printing by the same process. In these b', b², and b³ are the three transfer-rollers, f the collecting or printing form, f', f², and f³ the inking-forms. The operation of the device is exactly analogous to that of the flat-bed plate of Figs. 1 and 2 and needs no specific description. The transfer-rollers are grooved or fluted in the same manner, as is also the collecting-form, when desired.

Having thus described my invention, what I claim, and desire to secure by Letters Patent, is—

1. The process of multicolor printing which consists in depositing the various colors separately upon a common form as lines, which for each color lie at an angle not too acute with the lines of all the other colors and in taking the impression of all the colors from this form at once.

2. The process of multicolor printing which consists in depositing the various colors separately upon a common form as lines which, for each color lie at a different angle, certain

of said lines being interrupted where the lines of other colors are crossed, so that there is no superposition of moist colors, and in taking the impression of all said colors at once.

5 3. The process of multicolor printing from a single form which consists in depositing each of the various colors on said form as a minutely broken or interrupted surface so that the various colors may intermingle but not

overlap, and in then taking an impression of all the colors at once.

In witness whereof I have hereunto set my hand in presence of two witnesses.

MICHAEL RUDOMETOFF.
